UNITED STATES PATENT OFFICE.

DONALD C. DAVIS, OF DEPEW, NEW YORK, ASSIGNOR TO GOULD COUPLER CO., OF NEW YORK, N. Y.

BUFFER FOR RAILWAY ROLLING-STOCK.

1,339,743.

Specification of Letters Patent. Patented May 11, 1920.

Application filed December 3, 1917. Serial No. 205,007.

To all whom it may concern:

Be it known that I, DONALD C. DAVIS, a citizen of the United States, residing at Depew, in the county of Erie and State of New York, have invented a new and useful Improvement in Buffers for Railway Rolling-Stock, of which the following is a specification.

This invention relates to buffers for rail-way passenger cars, tenders and other rail-way rolling stock, and more particularly to a combined spring and friction buffer which extends outwardly from, or is located wholly in front of, the end sill of the car or other rolling stock to which the buffer is applied.

The objects of the invention are to provide a practical and desirable buffer adapted to be applied to and to extend outwardly or forwardly from the end sill of the car or other railway rolling stock and which has a very high and adjustable capacity and long travel with a low, easy and smooth recoil; and which preferably also enables the cars to be coupled up without bringing the friction resistance elements into action; also to secure these results in a buffer having a transversely arranged buffer head which is mounted, as usual, on central and side sup-30 porting stems and is adapted to swing horizontally so that the buffer heads of adjacent cars can remain in contact from end to end when the cars are rounding curves; also to provide a buffer of improved construction 35 in the other respects hereinafter described and set forth in the claims.

In the accompanying drawings:—

Figure 1 is a longitudinal sectional elevation of the end portion of a car or other railway rolling stock frame equipped with a buffer embodying the invention.

Fig. 2 is an end elevation of the buffer showing the end sill of the car in section.

Fig. 3 is a plan view partly in section 45 thereof.

Fig. 4 is a front elevation partly in section thereof.

Fig. 5 is a detail section thereof on line 5—5, Fig. 3.

50 A represents the end sill of a railroad car, tender or other railway rolling stock, hereinafter termed, for the sake of simplicity, a "car." B represents the car coupler which, as usual, is carried by a draw bar extending outwardly from the draft

gear beneath the end sill A. A metal end sill is shown composed of a vertical plate and angle bars secured to the upper and lower edges of the plate, but the buffer can be used with end sills of other construction. 60

The buffer comprises a housing 10 which is rigidly secured to the outer or front side of the end sill and projects outwardly therefrom, a buffer head or plate 11, center and side stems 12, 13, 13 to the outer ends of 65 which the buffer head or plate is pivotally connected, and spring and friction devices which are mounted in the housing 10 for yieldingly resisting the inward or buffering movement of the buffering head. The housing 10 and buffer head extend horizontally transversely of the car or parallel with the end sill A. The housing can be rigidly fixed to the end sill A by rivets 14, bolts, or other suitable fastening devices, extending 70 through the upright rear wall or plate 15 of the housing 10. The housing preferably consists of a single-piece integral casting provided between its ends with a central chamber 16 in which the friction resistance 80 devices are contained, and side chambers or pockets 17, 17 at opposite sides of said central chamber for the side buffer springs and side buffer stems 13, 13. Preferably, the housing or casting 10 is provided with a marginal strengthening flange 18, with strengthening or stiffening ribs or webs 19 extending from the side pockets or chambers 17 to the upright rear wall of the housing or casting, and is also provided below its central chamber or pocket with an integral block having 85

an upright front wall 20 against which the usual horn or projection 21 on the coupler is adapted to strike to limit the inward movement of the coupler and relieve the draft gear from strain when the coupler has been moved to the limit of its inward movement. This striking block as shown, is reinforced by upright ribs or webs 22 extending from the front wall 20 to the upright rear wall of 95 the housing or casting and from the bottom wall of the housing or casting to the bottom wall of the central chamber or pocket 16.

The side buffer stems 13 are preferably hollow or tubular and open at their rear 105 or inner ends and are arranged to slide or telescope in the side pockets 17 of the housing. 23 indicates buffer springs, one of which is located in each of the side pockets 17 with its ends bearing against the rear 110

walls of these pockets and against the outer ends of the hollow buffer stems. These springs coöperate with the friction devices, hereinafter described, to resist the inward movement of the buffer head. 24 represents stops or blocks which are bolted or otherwise secured to the housing or casting 10 and extend through the walls of the side pockets 17 into longitudinal slots in the sides of the hollow buffer stems 13. These stops limit the outward movement of the buffer head and prevent its displacement from the housing.

25 represents a wedge block which is located and adapted to move inwardly and outwardly in the central chamber 16 of the housing or casting, and 26 represents two wedge-shaped friction blocks which are arranged in the central chamber 16 of the housing at opposite sides of the wedge block 25 with their inclined inner faces contacting with the opposite inclined faces of the wedge block 25. The outer end of the wedge block 25 is adapted to engage stop flanges 28 at the front of the housing or casting at opposite sides of an opening 29 in the front wall thereof to limit the outward movement of the wedge block and prevent the displacement of the same from the chamber 16. The friction blocks 26 are adapted to move laterally or horizontally toward and from each other in the chamber 16 and are preferably guided between the upper and lower walls of the chamber 16 with their rear ends adapted to bear and slide against horizontal ribs 30 which extend across the rear portion of the chamber 16 and project forwardly from the rear wall of the housing or casting. These ribs strengthen the rear portion of the housing or casting and receive the rearward thrust of the friction blocks incident to the buffing action of the buffer.

31 represents bowed springs or spring plates which are arranged in the central chamber 16 between the end walls thereof and the outer sides of the friction blocks 26 for resisting the movement of the friction blocks outwardly or away from each other by the wedge block. Preferably there are two sets or groups of these springs for each of the friction blocks, said groups being arranged with their concaved sides facing each other and their ends in contact, and bearing centrally of their convex sides respectively against the friction block and the adjacent end wall of the central chamber 16. These springs or spring plates stand vertically in the chamber 16 and are adapted to be inserted into the chamber through openings 32 in the top of the chamber 16, closed by removable cover plates 33. The friction blocks 26 and the wedge block 25 can be inserted into the chamber 16 through the front opening 29 thereof, and the springs 31 then inserted through the openings 32.

When the wedge block 25 is forced inwardly or rearwardly in the chamber 16, it forces apart the friction blocks 26 and this movement is resisted by the spring plates 31. The spring plates and friction blocks 26 thus afford a frictional resistance to the inward movement of the wedge block. For moving the wedge block inwardly, the central buffer stem 12 is preferably provided, in front of the wedge block, with an enlargement or shoulder 34 adapted to engage the outer end of the wedge block when the buffer head has been moved inwardly a predetermined distance. In the normal position of the parts, shown in Figs. 1 and 3, this shoulder or enlargement is spaced forwardly from the end of the wedge block a sufficient distance to enable the inward movement of the buffer head necessary for coupling up the cars without engaging and moving the wedge block. Thus, in coupling the cars, the movement of the buffer head is resisted only by the side buffer springs 23 for the side buffer stems 13, and the friction resistance devices are not brought into action until after this preliminary movement of the buffer, which is sufficient for coupling up the cars.

In the buffing action of the device the inward movement of the buffer head is resisted by the side springs and by the central friction mechanism and owing to the arrangement of the buffer springs 23 at opposite sides of the friction mechanism, long and large springs can be employed. These springs can be large and strong enough to enable the inclined faces of the wedge block and friction blocks to have a relatively low pitch or slope and yet insure the release of the wedge block after it has been forced inwardly in the buffing action. When the wedge block is made of low pitch, which is necessary to give a long travel and easy or gradual recoil, very strong springs are required to insure the release of the wedge block. By the described arrangement two release springs for the wedge are provided and both of these can be large, heavy springs. It is thus possible to use lower-pitch friction blocks than would otherwise be possible and this enables a longer travel of the buffer head and a much more gradual and easy recoil or release.

The combined spring and friction resistance devices give a very high capacity and this capacity can be regulated by using a greater or less number of spring plates 31 for the friction blocks. The entire buffing mechanism is located in front of the end sill and this permits the floor of the car to be located lower than where the mechanism is located beneath the car floor.

I claim as my invention:—

1. A combined spring and friction buffing mechanism for railway rolling stock

- comprising a transversely elongated housing extending transversely of and projecting outwardly from the end of said rolling stock, a transversely extending buffer head 5 having a central and side supporting stems entering said housing for supporting the buffer head therefrom, a friction mechanism comprising a wedge block arranged to be moved inwardly in said housing by said central stem, friction blocks which are moved laterally in said housing by said wedge block, and springs in said housing for resisting the lateral movement of said friction blocks, and coil springs which are arranged longitudinally in said housing at opposite sides of said friction mechanism and bear against fixed parts of the housing to resist the inward movement of said buffer head, a lost motion connection being provided between the buffer head and said wedge whereby the wedge is not moved until after a preliminary independent resistance by said coil springs.
2. A combined spring and friction buffering mechanism for railway rolling stock comprising a transversely extending unitary housing having a central chamber for a friction resistance mechanism and side spring pockets at opposite sides thereof for side coil springs, a transversely extending buffer head, friction resistance mechanism located in said central chamber and including a wedge block, laterally movable friction blocks, and means for yieldingly opposing the movement of said friction blocks by said wedge, longitudinally arranged coil springs in said side spring pockets and bearing against the fixed inner ends of the pockets to resist inward movement of the buffer head, said buffer head having a central supporting stem coöperating with said friction resistance mechanism, and side stems which enter said side pockets and co-operate with said coil springs, said coil springs being arranged to offer an independent preliminary resistance to the movement of the buffer head before said friction 45 resistance mechanism comes into action.
3. A combined spring and friction buffering mechanism for railway rolling stock comprising a transversely elongated housing adapted to be secured to said rolling stock transversely thereof and project outwardly therefrom, a transversely extending buffer head having central and side supporting stems which project into said housing for supporting and guiding said buffer 55 head, a friction mechanism comprising a wedge block arranged to be moved inwardly in said housing by said central stem, friction blocks which are moved laterally in said housing by said wedge block, and 60 springs in said housing for resisting the lateral movement of said friction blocks, and coil springs which extend longitudinally in said housing at opposite sides of said friction mechanism and bear against 65 fixed parts of the housing to resist inward movement of said buffer head, said side stems being hollow and coöperating with said housing to inclose said coil springs, a lost motion connection being provided 70 between said central stem and said wedge block, whereby said coil springs offer a preliminary resistance to the movement of said buffer head before said wedge and friction blocks are actuated. 75

Witness my hand this 30th day of Nov., 1917.

DONALD C. DAVIS.
